LOUIS E. LEMLEY AND ROBERT N. LEOPARD, OF NEW ORLEANS, LOUISIANA.

AUTOMATIC CUT-OFF FOR GAS-STOVE BURNERS.

1,141,564.

Specification of Letters Patent.

Patented June 1, 1915.

Application filed April 15, 1914. Serial No. 832,093.

To all whom it may concern:

Be it known that we, LOUIS E. LEMLEY and ROBERT N. LEOPARD, citizens of the United States, residing at New Orleans, in the 5 parish of Orleans and State of Louisiana, have invented a new and useful Automatic Cut-Off for Gas-Stove Burners, of which the following is a specification.

This invention has reference to improvements in automatic cut-offs for burners of 10 gas stoves, and its object is to produce a mechanism which may be readily attached to the gas stove burners whereby the placing of a cooking vessel over a burner of the 15 gas stove causes the opening of the gas inlet, and the removal of the vessel causes a closure of the gas inlet, so that a failure to shut off the gas valve or an accidental or careless turning on of the gas valve will not cause 20 an escape of gas.

When the gas stove is in use, and the cooking utensils are placed thereon and taken off of the stove there is no waste of gas by failure to turn the gas valves off and the 25 operation of the stove may be assured by the employment of a pilot flame which may burn continuously while the stove is in use, wherefore the heating burners may be permitted to become automatically extinguished in the 30 absence of a cooking utensil, and will automatically light up when a cooking utensil is placed upon a burner.

The present invention contemplates a structure which may be applied to various 35 types of gas stoves without any change in the structure of the stoves interfering with the use of the stoves in the ordinary manner, and, also, the structure is such that it may be applied to ordinary gas stove burners in a 40 minimum of time and at a minimum of expense.

The invention will be best understood from a consideration of the following detailed description, taken in connection with 45 the accompanying drawings forming a part of this specification, with the further understanding that while the drawings show a practical form of the invention, the latter is not confined to any strict conformity with 50 the showing of the drawings, but may be changed and modified so long as such changes and modifications mark no material departure from the salient features of the invention.

55 In the drawings:—Figure 1 is a side elevation of a gas stove burner with the inven-

tion applied. Fig. 2 is a plan view of the structure shown in Fig. 1 with some parts in section. Fig. 3 is an end elevation of one of the burner valve receiving heads. Fig. 4 is an end view of a portion of the automatic attachment for the burner valve. Fig. 5 is a detail view of a modified portion of the structure.

In the drawings there is shown a gas 65 burner head 1 which may be taken as of ordinary construction, and this head has the usual gas conveying tubular extension 2 terminating at an appropriate distance from the burner 1 in a hood 3 to which is applied 70 a valve 4 held to the hood by a set screw 5 extending through a lug 6 on the face of the hood.

The parts described may be in general 75 typical of ordinary constructions customarily employed in connection with gas stoves, and so these parts need not be specifically described.

Applied to a portion of the tubular extension 2 near its point of junction with the burner head 1 is a stud 7 on the free end of which there is pivotally mounted a rock lever 8. One end of this lever has applied thereto a rod 9 so situated as to project upwardly through the center of the burner head when 80 the structure is installed, and at the upper end of this rod there is applied a tubular neck 10 projecting from a head 11, the neck carrying a set screw 12 designed to hold the neck to the rod 9 in any desired position of 85 telescoping adjustment. The neck 10 extends through a guiding stand or yoke 10^a made fast to the top of the burner head in any suitable manner. The neck 10 is long enough to carry the head 11 above the upper 90 surface of the usual grid 13 found in gas stoves.

Pivottally connected to the end of the rock arm 8 remote from the rod 9 is another rod 14 carried through a guiding lug 15 projecting from one side of the tubular extension 2, and the rod 14 adjacent to the lug 15 may be provided with a collar 16 between which and the lug 15 the rod is surrounded by a spring 17 tending at all times to move 100 the rod 14 in a direction to hold the head 11 a suitable distance above the surface of the grid 13. Instead of employing a spring for 105 this purpose, a weight 18 may be applied to the rock lever 8, say, at the junction of the rod 14 therewith, and this weight will tend at all times to hold the head 11 in the ele- 110

vated position, but like the spring will yield to a superior force applied to the head and tending to depress it.

The rod 14 terminates in a yoke 19 receiving one end of another rod 20, such end being flattened, as indicated at 21, and, entering the yoke 19, is held in adjusted positions therein by a set screw 22. The rod 20 constituting an extension of the rod 14 enters 10 the hood 3 through a perforation 23 formed therein, and extends entirely through the hood and beyond that face thereof remote from the burner 1 where the rod has applied thereto an adjustable stop member 24 held 15 in any desired position with respect to the rod by a set screw 25.

Offset from and fast to the rod extension 20 within the hood 3 is a finger 26 having a pin prolongation 27 arranged axially of the 20 gas valve 4. This valve terminates within the hood 3 in the usual neck 28 which in accordance with the present invention has applied thereto a hollow plug 29 having one end 30 reduced in diameter and from thence 25 flaring, as indicated at 31. The plug 29 may be screwed or otherwise secured in the neck of the valve 4 within the hood 3, and housed in the hollow plug is a ball valve 32, which may be prevented from escaping toward the 30 valve 4 by a stop pin 33 extending across the bore of the hollow plug 29, while the reduced end of the bore adjacent to the flaring end of the plug constitutes a valve seat for the valve 32, and the pin extension 27 is of such 35 length and diameter as to enter the bore of the plug through the flaring end so as to engage the valve ball 32 and unseat it by an appropriate longitudinal movement of the rod 14 and its extension 20.

40 To provide for an appropriate supply of air to the hood 3, that face of the hood remote from the burner 1 has a damper 34 thereon, which damper may be opened or closed to appropriate extents to regulate the 45 air needed for the proper combustion of gas entering the hood 3 by way of the valve 4 and ultimately escaping with a suitable quantity of air mixed therewith at the burner 1.

50 When it is desired to use the burner 1, or a stove supplied with several burners 1, the gas valve 4 of the burner, or the gas valves of two or more burners, are opened, whereupon the gas pressure at once drives the 55 valve ball 32 against its seat in the plug 29. This prevents any escape of gas after the valve 4 is opened, and while the grid 13 contains no cooking or other utensil. To save the necessity of lighting up the burner every time it is desired to use it, the stove 60 may be equipped with burners provided with the usual pilot burner which, however, is not shown in the drawings.

As soon as any suitable object is placed 65 upon the grid 13 it first contacts with the

head 11 and depresses it to the level of the upper surface of the grid 13. This movement is transmitted through the rod 9, lever 8, and rods 14 and 20 to the pin 27, which latter in the normal or inoperative position 70 of the parts is withdrawn from the bore of the plug 29. On depressing the head 11, however, the pin extension 27 enters the bore of the plug 29 through the flaring opening, and engaging the ball 32 dislodges it from its seat, so that gas will now flow into the tubular part 2 and from thence into the burner head 1, carrying sufficient air with it to sustain combustion, and the burner operates in the ordinary manner, the gas issuing 80 from the burner 1 being at once ignited by the pilot flame, which latter being a common expedient in stoves is not indicated in the drawings. As soon as the cooking or other utensil is removed from the grid 13, the 85 spring 17 or weight 18, as the case may be causes the return of the head 11 to the elevated position and such movement of the rods 14 and 20 as to withdraw the pin extension 27 from the path of the valve 32 and the force of the flowing gas at once moves this valve into its seat and holds it there, thereby shutting off the gas, although the valve 4 remains open.

So long as the stove is in use and cooking 95 utensils are being placed upon and removed from the burners, the valves 4 remain open, but gas is not burned uselessly since all the time the burner is not in use the gas is automatically cut off from it, and as soon as it is 100 put into use the gas is automatically turned on. Of course, when the stove as a whole, or any one of the burners is not to be used, the valve or valves 4 are turned off.

It sometimes happens that when the stove 105 is not at all in use the valve 4 may be accidentally or carelessly opened, but no harm results from such action, since no gas can reach the burner unless a cooking utensil be first placed thereon.

The whole invention may be applied to existing gas stoves at a minimum of trouble and expense, making the stove so changed automatic in action and unlikely to be accidentally turned on so as to cause escape of 115 gas.

What is claimed is:—

1. In a gas stove provided with a burner, a gas controlling valve, a conduit between the valve and burner, a valve casing connected to the discharge end of the burner and opening into the conduit in the line of flow of fluid therethrough and provided with a valve seat at the end toward the burner, a valve within the valve casing responsive to gas pressure to automatically close, a member associated with the burner and mounted for movement by articles placed over the burner, and connections between said last-named member and the valve 120 125 130 135 140 145 150 155 160 165 170 175 180 185 190 casing and provided with a terminal portion in position to enter the valve casing through the outlet end thereof to engage and dislodge the valve from the valve seat.

5 2. In a gas stove provided with a burner, a gas controlling valve, a conduit leading from the valve to the burner, a supplementary valve casing and valve housed therein and applied to the gas outlet of the main gas 10 valve, said valve casing having a flaring outlet in the line of flow of gas through the main gas valve, and the valve within the casing being freely responsive to flow of gas to seat against the smaller end of the flaring 15 outlet and closing said outlet, and means extending from the burner to the flaring opening of the supplementary valve casing and responsive to articles placed over the burner to then force the supplementary valve 20 against the action of the gas pressure from its seat.

3. In a gas stove provided with a burner, a main gas controlling valve, a conduit leading therefrom to the burner, a supplementary valve casing and valve therein carried by the discharge end of the main gas valve, said casing comprising a hollow plug with the end remote from that applied to the main valve reduced in diameter and then 25 flaring with the flaring portion constituting the gas outlet of the supplementary casing and the valve being in the form of a ball valve freely movable under gas pressure and in the direction of flow thereof to seat at the 30 small end of the flaring opening for closing the latter, a member located at the burner and movable by objects placed over the burner, and connections between said movable member and the supplementary valve 35 casing, said connections being provided with a terminal portion movable into and out of the supplementary valve casing to dislodge the ball valve when moved into said casing.

4. In a gas stove provided with a burner, a main gas controlling valve, a conduit leading therefrom to the burner, a supplementary valve casing and valve therein carried by the discharge end of the main gas valve, said casing comprising a hollow plug with the end remote from that applied to the main valve reduced in diameter and then 45 flaring with the flaring portion constituting the gas outlet of the supplementary casing

and the valve being in the form of a ball valve freely movable under gas pressure and 50 in the direction of flow thereof to seat at the small end of the flaring opening for closing the latter, a member located at the burner and movable by objects placed over the burner, and connections between said movable member and the supplementary valve 55 casing, said connections being provided with a terminal portion movable into and out of the supplementary valve casing to dislodge the ball valve when moved into said casing, 60 and said connections being provided with means constraining them toward the inactive position and also provided with means for adjusting the effective length of said 65 connections.

70 5. In a gas stove, the combination with a gas burner provided with a gas conduit leading therefrom, a terminal hood for the conduit, and a controlling valve entering the hood, of a hollow plug adapted to the discharge end of the valve, said plug having a valve seat therein and a valve responsive to gas pressure to move to the closed position, a rod carried by the tubular conduit and entering the hood and there provided with a 75 pin movable into and out of the valve plug into and out of engagement with the valve therein, direction-changing means mounted on the gas burner and connected to the rod, and another rod carried by the direction- 80 changing means and having a terminal portion in the path of an article placed in operative relation to the burner, both rods being provided with telescoping portions for the adjustment of their effective lengths, and 85 means for normally constraining the rods to the inactive position, the first-named rod being of a length to extend entirely through the hood and there provided with an adjustable stop means for locking the rod in 90 position to maintain the valve within the 95 valve plug in the open position.

In testimony, that we claim the foregoing as our own we have hereto affixed our signatures in the presence of two witnesses.

LOUIS E. LEMLEY.
ROBT. N. LEOPARD.
